HAND CARD

Filed Dec. 21, 1931

UNITED STATES PATENT OFFICE

HERBERT MIDGLEY, OF WORCESTER, MASSACHUSETTS; WORCESTER BANK & TRUST COMPANY, EXECUTOR OF SAID HERBERT MIDGLEY, DECEASED

HAND CARD

Application filed December 21, 1931. Serial No. 582,230.

The principal objects of this invention are to provide a more secure and also a more simple means for securing the foundation of the card-clothing to the back of a hand card 5 along the edges, and also to provide such a means which will neatly finish the edges of the card, thus providing not only a better and more durable card, but one of neater and more attractive appearance.

10 Other objects and advantages of the invention will appear hereinafter.

Reference is to be had to the accompanying drawing, in which

Fig. 1 is a view of the rear or top side of a 15 hand card constructed in accordance with this invention;

Fig. 2 is a sectional view on the line 2—2 of Fig. 1;

Fig. 3 is a sectional view of the card as 20 shown in Fig. 2, but on enlarged scale, and

Figs. 4 and 5 are front views of the opposite edges of the card taken at the corners as indicated respectively by the arrows 4 and 5 in Fig. 3.

25 Ordinarily the foundation 10 of the card-clothing which is used on a hand card is secured to the board 11 which constitutes the card proper by a row of tacks or nails along each edge. These are apt to get damaged in 30 the ordinary use of a hand card and, in case of any particularly rough usage, some of them come out and repairs have to be made. The card-clothing is likely not to assume its original position after some of these tacks have 35 been displaced and put back again.

According to this invention the opposite edges of the leather, or other, foundation of the card-clothing are held in by sheet metal strips which are applied in such a way that 40 the foundation can be stretched thereby securely over the edge of the back. This holds the card-clothing firmly along the two edges and there is practically no chance of the fastening means being displaced and its grip lost on the foundation at any point along the 45 edge.

In the top or rear surface of the board 10, which is formed of laminations of wood, preferably, is sawed a kerf 12 entering the wood at an acute angle, and located at the ex-

treme end of an inclined surface 13. In other words the kerf is introduced at the high point along this surface. A strip of sheet metal is applied to the back of the hand card by inserting its edge into the kerf, as shown at 14, 55 and it is bent almost at right angles and runs along the surface 13 to form an inclined portion 15. From that it is again bent to form a straight plain end 16 on the hand card, and then is given another right hand angle bent 60 to bring it into position to have a flange 17 resting on the foundation 10 of the card-clothing along the edge thereof. This sheet metal piece is provided with teeth 18 at its edge arranged nearly at right angles to the 65 part 17, and these are driven into the card-clothing.

It will be understood readily that these sheet metal bending and driving operations can be performed very easily by hand or machine in such a way as to get a firm grip on the edge of the foundation and to secure the metal strip firmly to the wooden back of the card. This security is made permanent as long as the foundation is pulled or subjected 70 to a strain drawing it away from this edge plate of sheet metal. The metal strip is secured firmly to the board as the parts 15 and 17 are on opposite sides of it and the parts 14 and 16 are also on opposite sides. 75

The opposite edge of the foundation is secured in a similar way, but the metal strip is provided with an end 20 extending into a saw kerf 21 located angularly in the end surface of the wooden back 11. It is bent to 80 provide a straight surface 22 along the end of the back and another flat surface 23 at right angles along the outer surface of the edge of the foundation. It also has teeth 18 which are driven into the card-clothing. 85

On account of the angles shown and described, in connection with these two sheet metal pieces, it will be seen that the first one described is not capable of being removed except by swinging it around and unbending 90 its angle. The second one described could be pulled outwardly in a direction parallel to the flange 20, but the teeth 18 resist this, and, of course, when it is originally put in, the foundation 10 is put under slight tension 100

before the respective teeth 18 are driven in. Also the extreme edges are driven in to the kerfs 12 and 21 so as to be permanently secured. Consequently the foundation is firmly anchored and cannot be removed. Not only do these metal strips anchor the foundation, but they serve as a guard over two edges of the back of the card and protect it from ordinary rough usage. Two end strips 10 25 are also used to finish the article, but they do not constitute a feature of this invention.

The handle 26 is set into a sheet metal socket 27 which is provided with an extension 28 riveted to the back and there is only a slight 15 interruption of the wall of the sheet metal strip at one side in order to provide a place for this handle.

Although I have illustrated and described only one form of the invention, I am aware 20 of the fact that changes can be made therein by any person skilled in the art without departing from the scope of the invention as expressed in the claims. Therefore, I do not wish to be limited to the exact form 25 shown, but what I claim is:—

1. As an article of manufacture, a hand card having a back, a layer of card-clothing on the front surface of the back comprising a foundation, and a strip of sheet metal having 30 teeth extending into the front surface of the foundation, said strip being located along the edge of said back, the rear edge of the sheet metal extending into a saw kerf in the back to hold it in position.

35 2. As an article of manufacture, a hand card comprising a wooden back and a piece of card-clothing on the front, means for holding the card-clothing against the back at one edge and a sheet metal strip at the other edge 40 having teeth projecting into the card-clothing and a portion just back of the teeth resting on the outer surface of the card-clothing, a part substantially at right angles thereto extending along the edge of the back, and an end 45 bent away at an angle and held in a saw kerf in the said back.

50 3. As an article of manufacture, a hand card comprising a wooden back having an inclined surface near one edge, card-clothing covering the front of said back, means for holding the card-clothing on the back at one edge, and a sheet metal strip at the other edge 55 of the back having teeth extending into the foundation on the front surface, a part extending along the front surface of the foundation, a portion at substantially right angles to the last named part extending along the edge of the back, and a portion extending along the inclined surface, and the back having a saw kerf along the edge of the inclined 60 surface, the edge of the sheet metal strip extending into said saw kerf and being held there by friction.

65 4. As an article of manufacture, a hand card comprising a back and a sheet of card-

clothing on the front of the same, means for holding the card-clothing at one edge of the back, and a sheet metal strip at the other edge comprising a flat portion having teeth at the edge entering the foundation of the card-clothing, a portion extending substantially at right angles thereto along the edge of the back and a portion extending at an angle to the last named portion, the back of the card having a saw kerf extending into the edge 70 thereof to receive the last named portion of the strip.

In testimony whereof I have hereunto affixed my signature.

HERBERT MIDGLEY.
